Primary Examiner — Jack Reickel*Assistant Examiner* — Keith J Wilson(74) *Attorney, Agent, or Firm* — Gudrun E. Huckett(57) **CLAIM**

The ornamental design for a filter for aquarium, as shown and described.

DESCRIPTION

FIG. 1 is a perspective view of a filter for aquarium showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown represent portions of a filter for aquarium and form no part of the claimed design.
